(57) **CLAIM**

The ornamental design for a charger cabinet, as shown and described.

DESCRIPTION

FIG. 1 is top right perspective view of a charger cabinet showing our new design;

FIG. 2 is a bottom right perspective view thereof;

FIG. 3 is a front elevation view thereof;

FIG. 4 is a back elevation view thereof;

FIG. 5 is left elevation view thereof, the right side being a mirror image thereto;

FIG. 6 is a top plan view thereof; and,

FIG. 7 is bottom plan view thereof.

The broken lines in the figures represent portions of the article which form no part of the claim.
